UNITED STATES PATENT OFFICE

159,041

AUTOMOBILE WINDSHIELD VISOR

Otto L. Bihlmire, South Bend, Ind.

Application January 17, 1949, Serial No. 1,072

Term of patent 14 years

(Cl. D14—6)

To all whom it may concern:

Be it known that I, Otto L. Bihlmire, a citizen of the United States, residing at South Bend, in the county of St. Joseph and State of Indiana, have invented a new, original, and ornamental Design for Automobile Windshield Visors, of which the following is a specification, reference being had to the accompanying drawing, forming part thereof.

Fig. 1 is a top plan view of an automobile windshield visor, showing my new design;

Fig. 2 is a view from the left-hand side of Fig. 1; and

Fig. 3 is a front elevational view.

I claim:

The ornamental design for an automobile windshield visor, as shown.

OTTO L. BIHLMIRE.
